CLAIM

The ornamental design for a candle holder, as shown and described.

DESCRIPTION**2.1: Perspective****2.3: Front****2.4: Top****2.5: Bottom**

The side views (front, back, right and left) are identical. The features shown in dash-dash lines in the drawing depict portions of the candle holder. The drawings contain symbolic jagged break lines in Fig. 2.1-2.3. The portions between the break lines forms no part of the claimed design. The dash dot dash lines define the bounds of the claimed design. The broken lines form no part of the claimed design.

1 Claim, 4 Drawing Sheets(56)
